MEANS FOR SHOOTING OIL WELLS

Orland C. Mays, Kermit, Tex.

Application March 4, 1938, Serial No. 193,818

1 Claim. (Cl. 102—4)

This invention pertains to a method of "shooting" deep wells to increase recovery of fluid therefrom.

The "shooting" of wells has been practiced for a number of years by the oil industry, sometimes with success and sometimes with disappointing results. By practical experiments over a period of some 20 odd years I have become definitely convinced (as have others) that the type of "shot" which effects one well favorably will not necessarily, or even probably, effect another well in the same manner. The underground formations differ. Different sands vary in physical characteristics, in compressive strength, elasticity, in degree of homogeneity. A harder formation does not react to a "shot" the same as a softer formation. The formations overlying and underlying a particular sand also affect the results produced in that sand by a "shot."

Since the primary purpose of "treating" a well in any manner is to make it produce the greatest total number of barrels of oil at the lowest possible cost per barrel, then the effect of a "shot" on the well must be seriously considered if the "shooting" method of treatment is to be used. If the "shot" breaks down the wall of the well and necessitates a five or six day "clean out" job, and a more or less continuous "cleaning out" treatment thereafter because of cave-ins, the cost of production may be very materially increased, instead of decreased.

Up to the present time, due to the difficulty of actually inspecting a hole after it has been "shot," and also due to the fact the explosive manufacturers have not been sufficiently interested in the problems of the oil industry as to make explosives of varying strengths and speeds, the effect of certain type "shots" on certain type formations has not even been generally determined. It might be said that there are as many positive "expert" opinions on this subject today as there are experts. Most of these experts do agree, however, that it is not the actual enlargement of the diameter of the hole proper which produces the best results, but the enlargement or increase of the effective surface area of the sand in communication with the hole. In other words fissures, or crevices extending radially outward from the hole in the production sand are sometimes created by a particular "shot." Sometimes these fissures extend for a considerable distance vertically along the hole, and sometimes not. At times the fissures may even extend into the formation above and/or below the sand being shot. This specifically illustrates the different effects produced by

different type "shots" on different type underground formations.

The speed at which an explosive expands has, so far as I know, been entirely ignored as a factor governing, or partially governing, the effect produced by the "shot" on a particular formation. As previously mentioned, this is so mainly because liquid nitroglycerine has been almost universally employed as the explosive and the mere varying of the quantity of the liquid nitroglycerine used per foot of sand does not in any way affect the rate of speed at which the liquid expands when detonated. If, as I have proven by experiment, the fissuring effect produced in the hole varies materially with the speed of expansion of the explosive used, then the only proper way of shooting a well to produce the desired results would be to employ "shots" having varying rates of expansion. Since it is also true that many "shots" extend a vertical distance within the hole up to 450 feet, and several different type formations may occur within this distance, then it would appear that shots made up of several different grades of explosives, each having a different rate of expansion, would be valuable. These are the reasons back of the conception of my invention.

The chief object of the invention, therefore, is to provide a method of "shooting" oil wells which will simultaneously produce substantially uniform results in several different types of underground formations, regardless of their varying physical characteristics.

Another object is to provide a method of "shooting" wells which will produce the desired effect on various different type underground formations with the least possible tearing down effect on the wall of the well.

Another object is to provide a method of "shooting" wells which makes possible the utilization of the maximum total expansion of the particular explosive used, yet at the same time permits the use of a slower speed of expansion, when needed, to produce a desired effect on different types of formations being "shot."

Another object is to provide a method of "shooting" wells which will produce a large underground surface area connecting with a well hole proper, extending over a certain vertical distance in the hole, even though formations having considerably different physical characteristics occur within that vertical distance.

Other objects of the invention will be better understood from the following description when read in connection with the accompanying draw-

ing, which are chosen for illustrative purposes only, and in which:

Figure 1 is a diagrammatic view illustrating the results produced in a well when present "shooting" methods are used;

Figure 2 is a similar view illustrating the results produced in the same well when my new method is used; and,

Figure 3 is an enlarged sectional view of the upper end of an explosive container, and the lower end of another container, with a detonator between.

The invention consists simply in employing different grades of explosives, each having a predetermined rate of expansion, so that when the entire column of explosive is placed in the well, the explosive having the proper rate of expansion to affect a particular type formation in a desired manner will be positioned adjacent that particular formation, and so that when the entire "shot" is detonated the results produced on the different formations being "shot" will be substantially uniform. Such a result and method is illustrated in Figure 2 of the drawing. Formation A is one that can best be fractured or fissured by an explosive having a comparatively slow rate of expansion, say 14,000 ft. per second, so that grade explosive is placed in the containers adjacent formation A. Likewise, formations B and C are formations which can best be fissured by explosives having rates of expansion of approximately 20,000 ft. per second and 26,000 ft. per second, respectively, so those particular grades of explosive are placed in the containers adjacent those respective formations. The results produced when the "shot" is detonated are marked by the dotted line in the figure. This line does not mean that the well is enlarged as a whole to that particular diameter, but it does indicate that the effective underground surface area bared by the "shot" is substantially uniform in the three different formations. This is in contrast to the results produced by an explosive having one particular rate of expansion, as illustrated in Figure 1, which is according to the presently used method of "shooting." It will be seen, as indicated by the dotted line illustrating the results produced by the explosion, that the explosive having an expansion rate of 26,000 feet per second was really suitable only for formation C. Formation B really should have been shot by an explosive having a slower rate of expansion in order to produce as good results as were produced in formation C, and an explosive having a still lower rate of expansion should have been placed adjacent formation A.

Conversely, had a column of explosive of smaller diameter but having the same rate of expansion, been used, the results still could not have been uniform, or even nearly so. At present, this varying of the diameter of the explosive containers is the only known method of even attempting to produce different results in the hole, and it is not in the least effective because the rate of expansion is not changed simply by reducing the quantity of explosive used per foot of sand. Containers of a 3½ inch diameter are the type most widely used, and when the diameter of the containers used is cut from 3½ inches to 2½ inches, there is a loss in total expansion of 50% since the quantity of liquid explosive per vertical foot is cut from 2 quarts to 1 quart. With my method the total expansion of the explosive used is utilized because the diameter of the container is not re-

duced. It is only the rate of expansion and not the maximum quantity of expansion which is changed. And I have definitely proven that there are a number of different types of underground formations which are not fractured or fissured satisfactorily by an explosive having a high rate of expansion, but are fissured in a very satisfactory manner by an explosive having substantially the same volume of expansion but a slower rate of expansion. A high speed explosive often tears out a large hole and increases the diameter of the hole in one particular formation, but the mere enlarging of the diameter does not produce the desired results; it is the fracturing or cracking of the formation which produces the desired increase in the surface area exposed to the well hole. Often, too, the enlarging of the hole diameter at one point, or over a certain vertical distance, causes the wall of the well to cave in from time to time, necessitating clean out jobs which not only cost money, but also lose valuable production time. A mere cavity would only increase the effective producing surface by the actual area of its immediate surface, while each crack produced which extends radially outward from the hole provides a very great increase in effective oil producing surface. Each crack is a channel through which oil may drain into the central hole.

Without some method of "shooting" which makes it possible to create these cracks in each different underground formation, according to its own individual physical characteristics, the desired increase in oil production cannot be obtained by "shooting." My method makes it possible to shoot each formation with the grade of explosive with which it should be "shot" to produce the desired cracks or fissures. The method comprises the use of containers of one diameter throughout the vertical column of the "shot," and the use of different grades or types of explosive having the desired predetermined rate of expansion to properly affect each different underground formation lying adjacent the column of explosive. With my method the diameter of the containers used would not have to be reduced in order to protect a particular formation against breaking down, tearing out, or caving in. Thus, surface area does not have to be sacrificed to prevent injury to the well hole, as must be done with the methods of shooting presently in use.

In practice, my method contemplates the testing of the various underground formations to be shot to ascertain their individual physical characteristics. A choice of explosives having the proper rate of expansion for each respective formation is then made, the correct number of containers (depending on their length) are then filled with the respective grades explosive to be used, each container, or spaced containers may be fitted with the usual detonator (all of which are designated in the drawing by the numeral 5), and the containers are lowered into the well (individually or in groups) and are anchored in the well so that the explosive having a rate of expansion to properly fracture a certain type formation lies adjacent that particular type formation in the hole. Last, a time bomb (designated in the drawing by the numeral 6) is preferably lowered into the hole to rest immediately adjacent the upper end of the uppermost explosive container, and when it explodes, the entire column of explosive is simultaneously exploded. Any other desired or suitable method or means of exploding the column may be used, however, and I do not

wish to be limited to the use of a time bomb in connection with my method.

One important thing to bear in mind, however, is the fact that each different grade of explosive, whether it has an expansion rate of 14,000, 20,000, 26,000 or more feet per second, should preferably be detonated at its maximum speed. To accomplish this I prefer to use a detonator preferably at the top of each individual container, but certainly at the top of each individual grade of explosive, which will detonate each separate grade of explosive at its maximum speed. The speed of expansion of the explosive is determined when it is manufactured and that speed cannot be increased regardless of the speed at which it is detonated. The predetermined speed of expansion of any explosive can, however, be lowered below its maximum because of weak or improper detonation. The detonators which I use are preferably pieces of dynamite having a sufficiently high nitroglycerine content to be more sensitive than the explosive charge to be detonated. Dynamite detonators in which the nitroglycerine content is as high as 85% are ordinarily satisfactory, and will set off the "14,000" grade of explosive at its maximum rate of 14,000 feet per second and will

also set off the "26,000" grade of explosive at "26,000" feet per second. These detonators may be in stick form or in any other form. In Figure 3 I have shown one form of dynamite detonator which I have found satisfactory for use with the particular type containers illustrated.

Having described and illustrated my method of shooting wells, I make the following claim:

A bomb for shooting oil wells formed through 10 strata of predetermined contrasting characteristics, said bomb comprising a plurality of containers of dimensions permitting them to be freely lowered into the well to be shot, said containers being mounted for suspension one below another 15 in position to dispose the containers in operative relation to the stratas when the bomb is lowered into the well, said containers being of substantially equal capacity and containing an explosive of a predetermined strength according to the 20 strata to be shattered thereby when an explosion occurs, and a detonator in cooperating relation to each container and being of sufficient strength to detonate the respective charges at their maximum rates of expansion.
